(57) **CLAIM**

The ornamental design for a desert fork, as shown and described.

DESCRIPTION

FIG. 1 is a side view of the dessert fork showing my new design, the opposite side view being a mirror image thereof. FIG. 2 is a top plan view of the dessert fork with chevron pattern.

FIG. 3 is a bottom plan view of the dessert fork with chevron slot pattern.

FIG. 4 is an enlarged front view of the dessert fork with chevron slot pattern.

FIG. 5 is an enlarged rear view of the dessert fork with chevron slot pattern; and,

FIG. 6 is a perspective view of the dessert fork chevron slot pattern.
